8 Claims. (Cl. 211—148)

ABSTRACT OF THE DISCLOSURE

A corner fastening means to secure the end of a shelf flange against an upright corner post in which an offset element carried by the flange a spaced distance from the flange end receives a screw through an opening therein for threaded engagement with the corner post whereby its tightening rigidifies the engagement. The engagement preferably includes a combination of guide nipples and thread reinforcements on the post for correctly locating the flange end.

The present invention relates to knockdown steel shelving of the type embodying vertically spaced horizontally disposed rectangular shelves which are releasably secured at their corners to vertical corner posts with a readily and easily secured novel corner fastening means between box flanges on the shelves and the walls of the posts to provide a novel, rugged interfitting relationship of excellent appearance which is of great strength with the interfitting shelves and corner posts drawn hard and rigidly against one another.

The shelves which are considered are of the type more particularly described in our application, Serial No. 362,150, now U.S. Patent No. 3,276,403 reference to which is hereby made, in which the shelves are lengthwise marginally reinforced by compound flanges of plural thickness. Briefly, the shelves are longitudinally provided with vertically extending marginal full box-type flanges, three walls of which are preferably further rigidified by the provision of coextensive longitudinally extending ribs therealong with the fourth wall of each box flange offset upwardly and preferably incorporating a double thickness of sheet metal adjacent to the top of the shelf. The corners of the shelves are notched or cut away to expose the ends of the thus rigidified box flanges and the exposed ends thereof are designed for clamping cooperation with the corner posts.

The corner posts themselves are of four sided box design, preferably with a medial slot through one of the walls. Opposite walls of the posts oppose the ends of the box flanges on the shelves with rib sections die struck therefrom which interfit with the open ends of box flanges. The fastening means draws the rib sections hard into and within the open ends of the box flanges with the walls of the corner posts bearing against the end edges of flanges and flange ribs. With this rigidity established between the corner posts and the longitudinal box flanges of the shelves, longitudinal rocking of the assembled shelving is eliminated even with high loading limits. Also transverse rocking of the shelving is restrained by the inherent rigidity of the shelves along their short transverse dimension.

Summary

The novel form of corner fastening means whereby the upright corner posts are securely clamped against the end edges of the box flanges, involves the use of a novel stamping with a tapering offset chute received in a slot in the inner wall of the box flange near the post which offset deepens toward the post and terminates in a wall almost parallel to the post. The wall is apertured to receive a fast-

2

ening bolt which preferably is in the form of a coarse threaded sheet metal screw having a reduced shank portion and a spherically shaped wall on the shank side of the head for engaging the stamping. The threaded end is received in a novel guided and canted manner in a hole in the wall of the post between two rib sections.

Means also are provided for latching the stamping in working position within the slot provided for it in the box flange so that both it and a bolt threaded therein are retained in "ready" position on the shelf member for all future shelf adjustments. They will not be dislodged thereafter from their "ready" position to fasten the shelf into position against the various corner posts even though the shelf be moved to different locations along the corner post.

The provision of a shelving unit and corner fastening means of the character briefly outlined above being the principal object of the invention, it is another object to provide a shelving unit wherein all of the elements associated with the fastening means are concealed from view without trim strips when the erection procedure has been completed.

Further objects of the invention contemplate a shelving unit wherein the principal constituent parts thereof are susceptible to conventional rolling processes and require for their completion no machining operations to the ends that the shelving as a whole may be manufactured at a low cost; a unit is provided which is rugged and durable and which will withstand rough usage and heavy loads; the unit may be assembled and disassembled with the aid of only a single tool, namely a screw driver; the assembled product possesses no sharp edges or corners and is devoid of abrupt protrusions; it allows for wide manufacturing tolerances; is attractive in its appearance and pleasing in its design; and is otherwise well adapted to perform the services required of it. These and further desirable features characterize the structure and production of embodiments of the present invention.

Other objects and advantages of the invention, not at this time enumerated, will readily suggest themselves as the nature of the invention is better understood.

In the accompanying one sheet of drawings forming a part of this specification an illustrative embodiment of the invention has been shown.

In these drawings:

FIG. 1 is a perspective view of knockdown steel shelving embodying the invention as converted to a cabinet design;

FIG. 2 is a fragmentary perspective view of a corner region of the shelving unit constructed in accordance with the principles of the present invention;

FIG. 3 is a sectional view taken substantially on the horizontal plane indicated by the line 3—3 of FIG. 2 and in the direction of the arrows;

FIG. 4 is a fragmentary side elevational view of the outside face of the left front and right rear post of FIG. 1 at the shelf fastening level;

FIG. 5 is a view similar to FIG. 4 showing the right front and left rear post;

FIG. 6 is a perspective view of the fastening clip taken externally of the flange;

FIG. 7 is a perspective view of side of the fastening clip received within the box flange of the shelf; and

FIG. 8 is a schematic view of the screw-to-post engagement showing the cant of the screw determined by the lead of the screw thread.

A knockdown steel shelving construction is shown in FIG. 1 adapted to provide a cabinet 5 having sliding doors 7, between vertically spaced shelves 12, end panels 19 and vertical posts 10 comprising the side legs of an inverted U-shaped channel member more particularly described later.

Referring now to the drawings in detail and in particular to FIG. 2 wherein one corner region of a shelving unit constructed according to the present invention has been fragmentarily illustrated, the unit involves in its general organization a series of four posts 10 (FIG. 1) and two or more shelves, one of which has been illustrated and designated in its entirety at 12 (FIG. 2). The various corner posts 10 and shelves 12 are identical in the structural characteristics.

The shelves 12 and corner posts 10 are rigidly secured together in their operative assembled relationship by means of counterpart fastening devices each of which includes an offset sheet metal stamping 14 and a fastening bolt 16 in the form of a modified elongated sheet metal screw. The stamping 14 constitutes a reaction member for assimilating the thrust of the fastening screw which serves to clamp the shelf 12 rigidly to the corner post 10 in a manner that will be described.

The shelf 12 is generally of rectangular configuration and it includes a horizontal planar shelf top portion 20 having downturned transversely extending marginal flanges 22 and downwardly and longitudinally extending marginal flanges 24. The transverse flanges 22 are single thickness flanges and are provided with re-entrant reverse bends (FIG. 3) at their lower edges for reinforcing purposes.

The longitudinal flanges 24 are box flanges and, as best seen in FIG. 3, each flange includes inside and outside walls 28 and 30 respectively, a bottom wall 32 and a dual thickness top wall 34. The walls 28 and 30 are reinforced by spaced apart reinforcing ribs 36, while the bottom wall 32 is reinforced by a single central rib 38. The upper edge region of the box flange 24 projects a slight distance above the horizontal plane of the planar body portion 20 of the shelf 12 by reason of a vertical connecting flange 40 between the body portion and top wall 34, the flange 40 constituting a marginal restraining flange to prevent supported objects from rolling or sliding from the upper surface of the shelf and as shown herein has a wood finish plastic sheet finishing surface 41 adhered thereto. The four ribs 36 are inwardly rolled ribs while the rib 38 in the bottom wall 32 is an outwardly rolled rib. The four corners of the shelf 12 are notched or cut-away as indicated at 42 (FIG. 3) for reception of selected regions of the corner posts therein in a manner that will be described, and adjacent to the posts the inner wall 28 of the box flange is apertured as at 18 to receive the stamping 14.

The details of the corner posts 10 are best illustrated in FIGS. 2 to 5. Each post is of rolled sheet metal construction, preferably of a heavier gauge metal than that of the shelf 12 and comprises a main body tubular-type member having parallel side walls 50 and 52, a front wall 54 and a longitudinal slot 58 between two halves 60 of the rear wall. At the levels where shelves are to be located (FIGS. 4 and 5), the side walls have vertically spaced rib sections providing nipples or rib sections 62 and a dimple 64 between them having a keyhole perforation 66 therethrough whose minor diameter is the root diameter of the bolt 16 with the major dimension being said root diameter plus the height of the thread 17 on one side of the bolt. The nipples 62 serve a three-fold purpose, viz. to interengage with the end of the box flange 24; to guide the bolt 16 into proper engagement with the perforation 66; and to reinforce the side wall 50 against the strain of the screw 16. The axis of the screw in its secured position is at an acute angle from perpendicular to the side wall 50 that is equal to the lead of the screw thread 17, and the key portion 67 of the keyhole is disposed vertically in the side wall where a thread 17a of the screw has its greatest angle with respect to the side wall 50 so that the diametrically opposite thread portion 17b is parallel to the face of the side wall 50 so that the screw is guided and supported in a predetermined angular canted relationship that supports and stabilizes the box flange 24 perpendicularly to the side wall 50 when tightened in place.

In this connection it is to be noted that the U-shaped

channel members forming the posts are identical with the key portions 67 arranged in the same direction thereon so that when bent to the U-shape shown the keyhole portions 67 are up in the right front post portion and down in the right rear portion and vice versa in the left hand channel member to assure the thread and bolt cant described that is desired for each corner of the shelf. This reduces to unity the inventory required for posts as well as unity of inventory for shelves, side panels, and other elements described.

Each vertical corner post 10 is adapted to seat within a corner notch 42 with the side 50 of the post opposing and bearing against the adjacent open end or rim of the box flange 24 as best seen in FIGS. 2 and 3 in squared relation.

The stamping 14 is of sheet metal construction and, as shown in FIGS. 6 and 7, is in the form of a stamping having a flat generally rectangular body 74 provided with a rectangular flat flange 76 which rests against the inner face of the box flange wall 28 around the aperture 18 therein. The central portion of the stamping is offset into the interior of the box flange in the form of a concave chute 78 ending in a wall 80 having an aperture 82 that is disposed normal to the side of the chute 78. The aperture is elongated to receive the thread 17 of the screw 16 freely therethrough. At the shallow end of the chute the stamping is cut and offset towards the box flange to form a finger tab 84 that snaps into place in the recess opening 18 with an interlocking relationship with the end edges thereof. The other end of the chute can also be notched and offset, but preferably is die struck to provide a groove 86 next to the flange 78 to engage over the edge of the abutting end of the aperture 18.

With or without a screw 16 in the opening 82 of the stamping, the offset 78 is moved into the aperture 18 with an endwise movement until the finger tab 84 passes into cooperating engagement with the edge of the aperture 18, whereupon the other end of the stamping is pressed into place with the cant of thread wall 80 camming the groove 86 into engagement with the opposite edge of the aperture 18. Thereafter the stamping may not be removed from its installed position and the shelf 12 may be handled without danger of the stamping, and screw therein, falling from its installed position preparatory to securing the shelf in place. In this connection, it is to be noted that the shank of the screw 16 is free of threads for a distance approximately equal to the working length of the full size threads 17 that extends into the post 10 whereby upon loosening the screw it is free to slide back through the opening 82 enough to clear the post face 50.

The proper hole 66 in the corner post 10 is then selected for the desired shelf elevation and the fastening screw 16 is started through this hole to make threaded engagement with the post. Tightening of the screw with the aid of a suitable tool such as a screwdriver, will bring the rib sections 62 of the corner post into register and engagement with the open end of the box flange 24, and upon final tightening of the fastening screw 16 the screw angle, the rib sections 62 and the dimple 64 will orient at the correct angle without danger of slippage or twisting and the end of the box flange 24 will be supported rigidly and solidly against the side face 50 of the post 10 against shelf sway.

The end panel for the shelving is shown at 19 with its front and back edges received in the slots 58. The panel is marginally notched at 90 to coincide with the pointed ends of the screws 16 to hold the panel in place. In assembling the panel, it is first slipped into place in the slots 58 before the screws 16 are tightened down, after which the ends of the screws will enter the notches and prevent disassembly. Although the head of the fastening screw 16 may be observed when the shelving is viewed from below and then only at the rear posts, such viewing of the shelving is seldom made when the shelving is put to use. Therefore the fastening is substantially concealed from view, yet if correction or change of a shelf is desired brief in-

spection indicates how it is to be readily accomplished. Having thus described the preferred embodiment of the invention and the advantages of the arrangement of the parts and their elements for the objects and results stated, it will be understood by others how various and further modifications can be provided without departing from the spirit of the invention, the scope of which is commensurate with the appended claims.

What is claimed is:

1. In a knockdown steel shelving unit, the combination of an elongated upright corner post of angular cross-section having a side wall provided with vertically spaced keyhole-type perforations therethrough with their elongations disposed vertically, a generally rectangular horizontally disposed shelf having a cut away corner contacting two adjacent side walls of the post, a depending rectangular box flange with spaced outer and inner vertical walls extending along a longitudinal edge of the shelf and terminally opening against said wall, said inner wall having an aperture therethrough spaced from said opening, said side wall having outwardly die struck rib portions above and below each perforation received within said flange opening between the inner and outer flange walls, fastening means for drawing the opening end of the flange into rigid contact with the side wall around said rib sections including a sheet metal stamping having a tapered offset chute received in said aperture with the taper deepening towards the post and terminating in a thrust wall having a bolt receiving aperture therethrough in alignment with said perforation, and a bolt extending through said bolt aperture at an acute angle to the side wall of the post and threadedly received in the perforation in a canted manner wherewith the thread of the bolt passes through the elongation of the perforation and approximately one-half turn of the thread beyond the perforation rests against the other side of the post wall whereby the bolt is disposed at an angle which with the thrust wall of the chute maintains said flange square to the side wall of the post.

2. In a knockdown steel shelving unit, the combination of a U-shaped support defining two upright corner posts of angular cross-section, each having a side wall provided with vertically spaced keyhole-type perforations therethrough at equal heights in said posts with their elongations disposed vertically upwardly in one post and downward in the other post, a generally rectangular horizontally disposed shelf cut away at the corners to engage two adjacent side walls of the posts and having depending rectangular box flanges each with spaced outer and inner vertical walls extending along opposite longitudinal edges thereof and terminally opening against said side wall of the two posts respectively, the inner vertical walls each having an aperture therethrough spaced from the respective openings, said side wall having die struck rib portions above and below each perforation received within the respective flange openings between the inner and outer flange walls, fastening means for drawing the end of each flange into rigid contact with the side wall around said rib portions against relative lateral displacement including a sheet metal stamping having a flanged tapered offset chute in the center received in each perforation with the taper deepening towards the post and terminating in a thrust wall having a bolt receiving aperture therethrough in alignment with the respective perforation, a bolt extending through each bolt aperture at an acute angle to the side wall of the post and at an obtuse angle with respect to each other and threadedly received in the respective perforations in a canted manner wherewith the thread of the bolt passes through the elongation of the perforation and approximately one-half turn of the thread beyond the perforation rests against the other side of the post wall whereby the bolt is disposed at an angle which with the thrust wall of the chute maintains the flanges square to the side wall of the post in rigid anti-end sway relationship.

3. In a knockdown steel shelving unit, the combination

of an elongated upright cross sectionally rectangular corner post having a side wall provided with vertically spaced perforations therethrough, a generally rectangular horizontally disposed shelf cut away at the corners to engage two adjacent side walls of the posts and having a depending rectangular box flange with spaced outer and inner vertical walls extending along a longitudinal edge thereof and terminally opening against said side wall, said inner wall having an aperture therethrough spaced from said opening, said side wall having outwardly die struck rib sections above and below each perforation received within said flange opening between the inner and outer flange walls, fastening means for drawing the open end of the flange into rigid contact with the side wall around said rib sections including a sheet metal stamping having a border flange engaging the face of the inner wall and a tapered offset chute in the center thereof received in said aperture with the taper deepening towards the post and terminating in a thrust wall having a bolt receiving aperture therethrough that is in alignment with said perforation, and a bolt extending through said bolt aperture at an angle to the side wall of the post and threadedly received in the perforation with a half turn of the thread beyond the perforation resting against the other side of the post wall whereby the bolt with the thrust wall of the chute maintains the flange square to the side wall of the post.

4. The combination called for in claim 3 wherein said bolt has a reduced shank portion between the head and its threaded end portion for free longitudinal retraction of the bolt in said bolt aperture to clear contact with said side wall and confine unto the threaded engagement its orientation in the fastening relationship.

5. In a knockdown steel shelving unit, the combination of an elongated upright corner post rectangular in cross section having a wall provided with vertically spaced perforations therethrough, outwardly die struck rib sections above and below each perforation and a generally rectangular horizontally disposed shelf having a depending rectangular box flange with spaced outer and inner vertical walls extending along a longitudinal edge thereof and terminally opening against said wall with the inner wall having an aperture therethrough spaced from said opening, said shelf and depending flanges being cut away at a corner region to receive the corner post therein and the rib sections within said flange opening between the inner and outer flange walls, fastening means for drawing the end of the flange into rigid contact with the side wall around said rib sections including a sheet metal stamping having a tapered offset chute received in said aperture with the taper deepening towards the post and terminating in a thrust wall having a bolt receiving aperture therethrough in alignment with said perforation, said stamping having oppositely extending convolutions on it engaging the edges of said aperture to support the stamping in said aperture against inadvertent removal, a bolt extending through said bolt aperture at an angle to the side wall of the post and threadedly received in the perforation in a canted manner wherewith the thread of the bolt passing through the perforation has a half turn beyond the perforation that rests against the other side of the post wall with a thrust on the thrust wall of the chute by the head of the bolt that maintains the flange square to the side wall of the post, said bolt having a reduced shank portion between the head and threaded end portion for free longitudinal retraction of the bolt in said bolt aperture to clear contact with said side wall when not in its fastening relationship.

6. In a knockdown steel shelving unit, the combination of a U-shaped support defining two upright corner posts having facing walls defining a longitudinal medial slot and coplanar side walls provided with vertically spaced keyhole-type perforations therethrough at equal heights in said posts with their elongations disposed vertically upwardly in one post and downward in the other post, a panel received edgewise in said slot and having edge

notches at a level coinciding with perforations in the side wall, a generally rectangular horizontally disposed shelf having depending rectangular box flanges each with spaced outer and inner vertical walls extending along opposite longitudinal edges thereof and cut away at the corner regions to terminally contact said panel and receive the corner posts against the open ends of the flanges, the inner vertical walls of the flanges each having an aperture therethrough spaced from the respective opening, said side wall of the post having die struck rib portions above and below each perforation received within the respective flange openings between the inner and outer flange walls, fastening means for drawing the end of each flange into rigid contact with the side wall around said rib portions against relative lateral displacement including a sheet metal stamping having a flanged tapered offset chute in the center received in each perforation with the taper deepening towards the post and terminating in a thrust wall having a bolt receiving aperture therethrough in alignment with one of said perforations, a bolt extending through each bolt aperture at acute angles with respect to the side wall of the post and flange and threadedly received in the respective perforations in a canted manner wherewith the thread of the bolt passes through the elongation of the perforation and approximately one-half turn of the thread beyond the perforation rests against the other side of the post wall with the end of the bolt engaging in one of said notches whereby the bolt is disposed at an angle which

with the thrust wall of the chute maintains the flanges square to the side wall of the post in rigid anti-end sway relationship and the panel in place as well as exposing the head of the screw inwardly of the flange for axial alignment with a screw driver bit during assembly and dismantling operations.

5. The combination called for in claim 6 in which said bolt has a reduced shank portion between the head and threaded portion for free longitudinal retraction of the bolt through said bolt aperture to clear said notch and relinquish contact with said side wall.

10. The combination called for in claim 6 in which said sheet metal stamping includes a border flange engaging the face of the inner wall of the flange around said aperture and said stamping has oppositely extending elements 15 engaging the edges of said aperture to readily receive and support the stamping in said aperture against inadvertent removal.
